UNITED STATES PATENT OFFICE.

DANIEL D. SHAW, OF DENVER, COLORADO.

MOTOR.

SPECIFICATION forming part of Letters Patent No. 509,052, dated November 21, 1893.

Application filed March 13, 1893. Serial No. 465,835. (No model.)

To all whom it may concern:

Be it known that I, DANIEL D. SHAW, a citizen of the United States of America, residing at Denver, in the county of Arapahoe and State of Colorado, have invented certain new and useful Improvements in Mechanical Powers; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in pump operating mechanism, and the object of the invention is to improve the machine described in Letters Patent of the United States, No. 489,419, issued to me, bearing date January 3, 1893, and to this end the mechanism consists of the features, arrangements and combinations hereinafter described and claimed, all of which will be fully understood by reference to the accompanying drawings, in which is illustrated an embodiment thereof.

In the drawings, Figure 1 is a side elevation of the mechanism. Fig. 2 is a top or plan view of the operating parts, the upper portions of the mechanism being removed. Fig. 3 is a plan view of the base of the machine, illustrating the pump cylinders and showing their connections with the central chamber. Fig. 4 is a top or plan view of the machine, the adjustable top frame being partly broken away. Fig. 5 is a fragmentary view in perspective of the movable spring actuated plate which returns the pivoted arm to its upward limit of movement after each downward stroke. Fig. 6 is a fragmentary view in perspective of one of the pivoted arms which operate the pumps.

Similar reference characters indicating corresponding parts or elements of the mechanism in the several views let the numeral 5 designate a stationary base supporting the pump cylinders 6, connected with the supply source by pipes 7 and provided with outlet conduits 8, leading to the central receiving chamber 9, provided with a discharge pipe 10 at the bottom. The piston rod 12 of each pump cylinder is movably connected at its

upper extremity with an arm 13 provided with a curved shank 13^a that passes under the outer rim of the upper stationary platform 14 and passes upward to a forked bracket 15, carrying a socket in which the arm extremity is pivoted and retained. Bracket 15 is composed of some suitable metal and made of sufficient strength to support the arm when acted on by the mechanism hereinafter described. This construction of the arms 13 together with the manner of attaching them to the outer rim of the platform, constitutes one important improvement over that shown in the patent heretofore issued to me, since in my previous construction it is necessary to cut away the material of the platform's rim, whereby the latter is greatly weakened, in order to form suitable recesses for the reception of the arms attached to the pump pistons. By forming the arms curved, and passing them under the rim as in my present construction, I avoid the necessity of forming recesses in the rim, since the free extremities of the arms are interiorly located with reference to the rim's inner circumference. Hence the rim of the platform remains intact and at the same time affords the support for the arms. The platform 14 is supported by legs or standards 16 connected with the base 5. Movable connected with the outer extremity of arm 13, is a rod 17 forked at its lower extremity, as shown at 17^a and secured to a vertically movable plate 18 apertured at each extremity as shown at 18^a, and carrying depending sleeves 18^b. The openings in these sleeves coincide with the apertures in the plate which is supported by coil-springs 19 which are attached to the extremities of plate 18 outside of the guide rods 20 and to the platform 14 above. These guide rods pass through the apertures in plate 18 as well as the depending sleeves which give the plates an elongated bearing on the rods which are stationary and secured between the base 5 and the platform 14. Suitably secured to the top platform 14 and supported thereon, are the vertical rods 22, passing through suitable apertures formed in the lugs 23 projecting exteriorly from the rim 24, provided with radial arms 25^a, and centrally guided and retained in place by the post 26 journaled upon platform 14. The rim 24 is

made fast to and actuated by the post 26. Rods 22 are provided with coil-springs 39 surrounding the same and located above the movable frame 24. Nuts 38 are placed upon the extremity of the rods to permit any suitable adjustment of the parts located between them and the platform 14. Suitably attached to the rim 24 and depending therefrom are the rollers 25, engaging the upper surface of the rim of wheel 27 made fast to the post 26.

The function of the rim 24 and rollers 25 is to maintain the wheel 27 in operative relation with the disks 35 hereinafter described. Were it not for said rim and its rollers, the cogged portion of the wheel 27 might under some circumstances slip from engagement with the peripheries of said disks, by virtue of the yielding quality of the metal composing the wheel which without the mechanism in question, would have only the post 26 to maintain it in operative relation with the disks. It is believed that the length of the wheel's radius would be such that it would be unsafe to rely upon the wheel's rigidity to maintain it at all times in engagement with the disks mentioned.

The cogged periphery of wheel 27 is engaged by a pinion 29 made fast to the upper extremity of a vertical shaft 30 provided at its lower extremity with a bevel pinion 31, meshing with another similar pinion 32 made fast to a short horizontal shaft 33 journaled in a box 34 secured to the base 5.

Power is applied to the machine by rotating the shaft 33 which is provided with a pulley 34^a which may be connected with any suitable motor.

Wheel 27 is supported from below by the disks 35 which are pivoted upon the periphery of a horizontal wheel 36 made fast to post 26 and rotating therewith. Disks 35 are of a diameter equal to the distance between wheel 27 and the platform 14. The outer part of the face of disks 35 is cogged as shown at 35^a to engage the correspondingly cogged track 14^a formed upon platform 14. The arms 13 lie in the path of the disks 35, the inner portion of whose face is smooth as shown at 35^b to make a proper bearing therefor. The smooth portion of the disk's face does not engage the rim but projects over its inner circumference to engage the arms 13 which lie in their path. The outer face of rim 36 is also provided with smaller rollers or disks 41 and 42 suitably pivoted on the rims. The rollers 35, 41 and 42 are arranged on their supporting rim in sets or groups, each set consisting of one roller of each kind. Of these rollers or rotating disks, 35 is the largest, 42 the smallest and 41 of an intermediate size. There are four sets of these rollers shown in the drawings and each set acts upon each arm 13 during each rotation of the wheel 36, whereby these arms are depressed so that they lie in the same horizontal plane with the upper surface of platform 14, the

piston rods 12 being correspondingly depressed. The rim 36 is rotated in the direction indicated by the arrows in Fig. 2, whereby by rollers 42, or the smallest rollers of each set engage and act upon the arms 13, first, giving them a partial downward movement, then follow the rollers 41 next in size which act to further depress the arms, after which the disks 35 complete the downward movement of the arms and the corresponding stroke of the piston rods. It will thus be seen that by reason of the cogged connection between the disks 35 and the rim 36, the power is much more efficiently and advantageously applied than when this connection is simply frictional as shown in my previous patent. The rods 17 and their plates 18 are also simultaneously and correspondingly depressed, the springs 19 being stretched or placed under tension by the downward movement of said plates. As soon as the last roller (35) of any set leaves the arm 13 the latter is immediately returned to its upward limit of movement through the medium of rod 17 and plate 18 which is suddenly carried upward by the recoil of springs 19, to its original position ready for engagement by the next set of rollers.

It will thus be seen that my present construction is materially different from that shown in Patent No. 489,419 and it is believed that important advantages are gained over the mechanism previously patented, not only from a standpoint of simplicity and economy of construction, but also in points of efficiency and general utility.

Having thus described my invention, what I claim is—

1. In a mechanical power, the combination of a suitable framework composed of a base and an upper platform supported thereon, of one or more inclined arms, pivoted on the upper platform at one extremity and supported by spring-actuated rods at the other extremity, and a horizontally rotating wheel made fast to a vertical shaft journaled in the framework and one or more disks pivoted on the periphery of said wheel, the face of these disks being partly cogged and partly smooth, the cogged portion engaging a cogged track formed on the stationary platform, while the smooth part engages the inclined arms which are forced downward against the upward tendency of the spring-actuated rods, which impart to the arms the upward movement as soon as the disks leave them, substantially as described.

2. In a mechanical power, the combination of a suitable frame-work having a circular cogged track, one or more oscillating arms pivoted on the frame-work, a horizontally rotating wheel mounted on the frame and carrying one or more pivoted disks having a cogged face to engage the track on the frame, and a plain face to engage the arms which are moved downward thereby, and spring-actu-

ated rods connected with the arms, and giving them their upward movement, substantially as described.

3. In a mechanical power, the combination 5 of a frame-work, oscillating arms pivoted thereon, a vertical shaft journaled in the frame, a power wheel made fast to the shaft, another wheel also made fast to the shaft and carrying disks pivoted on its periphery, such 10 disks having a cogged face to engage tracks formed on the power wheel and stationary frame, and a plain face to engage the arms, substantially as described.

4. In a mechanical power, the combination 15 of a suitable stationary frame-work, oscillating arms pivoted thereon and means for moving said arms in one direction, consisting of stationary rods, a plate slidingly supported thereon, coil-springs attached to the plate and 20 to the stationary platform, and another rod connected with the plate at one extremity,

and with the oscillating arm at the opposite extremity, substantially as described.

5. In a mechanical power, the combination 25 of the stationary frame, the oscillating arms pivoted thereon, and means for imparting to said arms movement in one direction, consisting of a horizontally rotating wheel mounted on the frame-work, and carrying a set of disks of different sizes pivoted on the 30 rim, and adapted to successively engage the arms, the largest of these rollers being provided with a cogged face to engage a track formed on the frame, and a plain face to engage the arms, substantially as described. 35

In testimony whereof I affix my signature in presence of two witnesses.

DANIEL D. SHAW.
